UNITED STATES PATENT OFFICE.

JOSEPH A. MANAHAN, OF NEW YORK, N. Y., ASSIGNOR TO WAYSIDE CORPORATION, OF NEW YORK, N. Y., A CORPORATION OF NEW YORK.

DESIGN FOR AN EDIBLE FOOD PRODUCT.

Application filed May 27, 1925. Serial No. 13,580. Term of patent 14 years.

To all whom it may concern:

Be it known that I, JOSEPH A. MANAHAN, a citizen of the United States, residing at New York, in the county of New York and State of New York, have invented a certain new, original, and ornamental Design for an Edible Food Product, of which the following is a specification, reference being had to the accompanying drawing, forming part thereof.

Fig. 1 is a top plan view of the edible food product containing the design of this invention.

Fig. 2 is a side view.

Fig. 3 is a bottom view.

Fig. 4 is an end view.

The edible food product embodying my design consists of a frankfurter partly encased in dough.

I claim:

The ornamental design for an edible food product substantially as shown and described.

JOSEPH A. MANAHAN.
